UNITED STATES PATENT OFFICE.

EDWARD WESTBERG, OF LOS ANGELES, CALIFORNIA.

PLASTER BOARD.

Application filed December 22, 1924. Serial No. 757,396.

This invention relates to plaster boards, and the object of the invention is to provide a plaster board embodying various improvements over such boards now in use. 5 Briefly, these improvements include the covering of the board with a waterproof material, preferably paper, in the manner hereinafter specifically described, and the forming of the outer surface of the paper 10 into a plurality of depressions and projections. The particular construction and arrangement of these improvements will be apparent from the following description, taken in connection with the accompanying 15 drawing. It should be understood, however, that while in such drawing I have illustrated one specific embodiment of my invention, the invention can be otherwise embodied within the scope of the appended 20 claims, without departing from the spirit thereof.

Referring to the figures of the drawing,

Fig. 1 is a fragmentary view of a sheet of my improved plaster board;

25 Fig. 2 is a cross-sectional view thereof;

Fig. 3 is a fragmentary cross-sectional view, showing a modification of the invention.

As illustrated, my improved board 30 comprises a plaster board composition 1, of a desired thickness, covered preferably on both sides thereof with paper coverings 2 and 3. Preferably both of such coverings are of waterproof material, as illustrated 35 in the drawing, though obviously only the covering 2 need be waterproof, if desired.

The paper coverings can be of any desired 40 form, though the outer and exposed surface thereof is preferably unsized. In Figs. 1 and 2 the outside or exposed surface of each covering 2 and 3 is unsized, and the inner surface, next to the board composition 1, is waterproof. In Fig. 3 both sides 4 and 5 of the paper covering are unsized and contain a waterproof layer 6 there-between.

This latter form at present is believed to be preferable, for various reasons.

Another novel feature of my invention is the forming of the outer or plaster-receiving side 2 of my improved board with a 50 plurality of indentations 7 and projections 8. These indentations and projections are preferably formed in the arrangement shown in the drawing, whereby such surface of the board is given an undulating 55 contour. It will be obvious that such a surface will receive the plaster in a manner forming a more perfect bond to hold the plaster secured to the board.

It is believed that the several improvements and advantages of my invention will be clear without further description herein.

What I claim and desire to secure by Letters Patent is:

1. An improved plaster board comprising 60 the combination of a plaster board composition having both sides thereof covered with paper, the surface of one of said sides of the board being formed with a plurality of projections thereon and indentations 70 therein, said projections and indentations being spaced apart in staggered relation both longitudinally and transversely of the board whereby the surface of the board having the projections and indentations will be 75 undulated both longitudinally and transversely of the board.

2. An improved plaster board comprising 80 the combination of a plaster board composition having one side thereof covered with paper, the paper having a waterproof layer adjacent the composition, the other side of the board being formed with a plurality of knob-like projections spaced apart both longitudinally and transversely of the board 85 and relatively staggered, and a plurality of indentations formed intermediate said knob-like projections and spaced therefrom.

EDWARD WESTBERG.
